POCKET STAMP

Filed April 28, 1927

INVENTOR.

Erwin Luther Terry,

BY

Geo. P. Kimmel.

ATTORNEY.

UNITED STATES PATENT OFFICE.

ERWIN LUTHER TERRY, OF TUCKERMAN, ARKANSAS.

POCKET STAMP.

Application filed April 28, 1927. Serial No. 187,293.

This invention relates to a pocket stamp for stamping the name, occupation and address of a person, or the name and address of a corporation, company, firm, etc., when occasion requires, but it is designed primarily for one stamping his name and address upon a hotel register to dispense with the writing of the same, but it is to be understood that a stamp, in accordance with this invention can be used in any connection for which it is found applicable, and the invention has for its object to provide, in a manner as hereinafter set forth a foldable and extendible article of such class constructed and arranged, that when folded, it will correspond to the shape of the body of a fountain pen whereby the article can be conveniently carried in the pocket of or removably connected to a garment.

Further objects of the invention are to provide, in a manner as hereinafter set forth, a pocket stamp which is simple in its construction and arrangement, strong, durable, compact, having the appearance of a fountain pen when closed, thoroughly efficient in its use, conveniently extended for the purpose of stamping and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is an elevation of a pocket stamp, in accordance with this invention, when closed.

Figure 2 is an elevation of the stamp in a partly extended position.

Figure 3 is a vertical sectional view of the stamp when extended for stamping purposes.

Figure 4 is a section on line 4—4 Figure 1.

Figure 5 is a section on line 5—5 Figure 3.

Figure 6 is a section on line 6—6 Figure 2.

A pocket stamp, in accordance with this invention includes a tubular retainer which is constructed of any desirable material and is formed with a closed end 2 and an open end 3. The retainer 1, at a point adjacent its

open end 3 is provided with peripheral threads 4 for engagement with an interiorly threaded removable cap 5 which acts as a means for closing said open end 3. When the retainer and cap are connected together, the former appears similar to the body portion of a fountain pen. The diameter of the retainer 1 is such that it can be conveniently handled, as well as enabling it to be readily mounted or inserted in the pocket of a garment, and further when inserted in a pocket of a garment, it will not impart a bulging effect to the outer wall of the pocket. Furthermore the diameter of the retainer is such that it can be conveniently connected with a garment by the well known form of clasp now employed for such purpose for fountain pens and pencils.

The retainer 1, has the body thereof, formed with a lengthwise extending slot having a pair of end walls 6, 7 and with the former of greater length than the latter. The slot further includes a side wall 8 which extends in the same plane throughout and terminates at opposed ends of the walls 6, 7. The slot 8 further includes another side wall formed of a pair of end portions 9, 10 and an intermediate portion 11 which is disposed at right angles with respect to the portions 9 and 10. The portion 9 terminates in the end wall 7 and in the outer end of the intermediate portion 11 and the portion 10 terminates in the inner end of the intermediate portion 11 and in the end wall 6. The portion 11 provides for the portions 9 and 10 to extend in parallel planes. The portions 9 and 10 oppose the end wall 8, but the portion 9 is arranged nearer the side wall 8 than the portion 10 and by setting up one of the side walls of the slot with the end portions 9 and 10 and intermediate portion 11 the slot is provided with a wide part 12 and a narrow part 13. The wide part 12 is positioned between the intermediate portion 11 of the side wall of the slot and the closed end 2 of the retainer and the narrow portion 13 is positioned between the intermediate portion 11 of the side wall of the slot and the peripheral threads 4 of the retainer. The intermediate portion 11 provides a shoulder to constitute a stop for a shiftable element to be presently referred to and the end wall 7 also provides a slot for a shiftable element to be presently referred to.

Mounted within the retainer 1 and adapted to be extended therefrom, when the cap 5

is removed, is an inverted yoke-shaped carrier referred to generally by the reference character 14 and having its head indicated at 15 and its arms at 16, 17. Each of said arms at a point between its transverse median and its inner end is formed with a lengthwise disposed slot 18. The slots of said arms align with each other. Secured to the carrier in proximity to the head 15 and secured to the arms 15 and 17, is a shifting element for the carrier and it consists of a bar 19 having its outer end provided with a knob 20. The bar 19 extends at right angles with respect to the carrier and further projects through the wide portion of the slot in the retainer. The shoulder formed by the intermediate portion 11 of a side wall of the slot, in the retainer 1, acts as a stop to arrest the shifting of the bar 19 in a direction towards the open inner end 3 of the retainer. The path of the bar 19 is to one side of the longitudinal center of the wide part 12 of the slot in the retainer 1. When the carrier is extended from its retainer 1 it will be in the position as shown in Figures 2 and 3 of the drawings.

Arranged at the free ends of the arms 16, 17 is a pair of stamp heads 21, 22 and to the outer face of each of said heads is secured a stamping or impressing member 23 provided with any matter to be stamped. By way of example the stamp member carried by the head 21 may be provided with the name of an individual and the stamp member carried by the head 22 the address and occupation of the individual, however it is to be understood that the stamp members can be provided with any suitable matter which is to be stamped. The heads 21, 22 when the carrier is extended project at right angles with respect to the side faces of the arms 16, 17. The inner or upper face of each head 21, 22, at the inner end thereof is formed with a tubular lug 24. The lugs 24 are arranged between the arms 16, 17 and each lug 24 is pivotally connected as at 25 to the lower ends of said arms. By this arrangement the heads 21, 22 are pivotally connected at their inner ends with the lower ends of the arms and can be swung towards the side edges of the arm, in a manner as shown in Figure 2.

Coacting with the heads 21, 22 for the purpose of swinging them to a position at right angles with respect to the arms 16, 17, as well as for swinging them to oppose the side edges of such arms, in a manner as shown in Figures 3 and 2, is a pair of oppositely extending shifting members 25, 26. The member 25 is pivotally connected at its outer end, as at 27 to the upper face of the head 21 approximately at the transverse median thereof, and the member 26 is pivotally connected at its outer end, as at 28 to the upper face of the head 22, approximately

at the transverse median of the latter. The member 25, centrally of its inner end, is formed with a tubular extension 29 which is positioned between a pair of tubular extensions 30 formed at the inner end of the member 26. The tubular extensions 29 and 30 align with each other and extending therethrough is a combined pivot and actuating or shifting element for the members 25, 26. The said combined pivot and actuating or shifting element for the member 25, 26 consists of a bar 31 which extends through the slot 18 and has its inner end formed with a head 32 and its outer end with a knob 33. The bar 31 operates in the slot formed in the retainer and the knob 33 is arranged exteriorly of such knob. The bar 31 when shifted travels through the major part of the wider portion 12 of the slot and entirely through the narrow part 13 of the slot. When the bar 16 is shifted to the position shown in Figure 2, the heads 21, 22 will be arranged to oppose the side edges of the arms 16, 17, but when the bar 21 is shifted to the position shown in Figure 3, the shifting members 25, 26 will extend at opposite inclinations thereby positioning the heads 21, 22 in endwise opposed alignment and which will enable the stamping action to be carried on. The members 25, 26 ride against the open end of the retainer 1, when the bar 31 or bar 19 is shifted towards the closed end 2 of the retainer 1 and the bars 25, 26, will move towards each other and which will provide for swinging the heads 21, 22 to the position shown in Figure 2. The shifting of the members 25, 26 to extend the heads 21, 22 to the position shown in Figure 3 is had after the bar 19 has its movement arrested by the shoulder formed by the intermediate portion 11 of one of the side walls of the slot formed in the retainer 1. When the knobs 20 and 33 are in the position shown in Figure 1 the carrier together with the members 25, 26 and heads 21, 22 will be completely enclosed by the retainer 1, after which the cap 5 is secured to the threads 4. When stamping, on positioning the thumb or finger against the knobs 20 and 33, the carrier 14 will be prevented from moving upwardly into the retainer.

It is thought the many advantages of a foldable pocket stamp, in accordance with this invention, can be readily understood, and although the preferred embodiment of the invention, is as illustrated and described, yet it is to be understood that changes in the details of construction can be had which will fall within the scope of the invention as claimed.

What I claim is:

1. A device for the purpose set forth comprising a tubular retainer, a carrier arranged therein and normally completely enclosed thereby, a pair of oppositely shiftable

impression member carrying elements pivotally connected at their inner ends to one end of the carrier, a pair of shifting members for said elements pivotally connected therewith, means for shifting said carrier for a portion of its length from said retainer and further for shifting said members for a portion of their length from said retainer, said last mentioned means slidably connected to the retainer and fixed to the carrier, and means connected to said members for shifting them after the first shift thereof to provide for the positioning of said elements at right angles with respect to the carrier, said last mentioned means pivotally connected to said members and slidably connected to said carrier and said retainer.

2. A device for the purpose set forth comprising a retainer, a carrier normally completely enclosed by said retainer, impression member carrying elements pivotally connected to the carrier, actuating means connected with said elements for moving them to and from stamping position, and means connected with said actuating means, carrier and retainer for bodily shifting said carrier and actuating means together for a portion of their length from the retainer and for shifting the actuating means independent of the carrier to move said elements to and from stamping position.

3. A device for the purpose set forth comprising a retainer, a carrier normally completely enclosed by said retainer, impression member carrying elements pivotally connected to the carrier, actuating means connected with said elements for moving them to and from stamping position, means connected with said actuating means, carrier and retainer for bodily shifting said carrier and actuating means together for a portion of their length from the retainer and for shifting the actuating means independent of the carrier to move said elements to and from stamping position, and means to arrest the shifting of the carrier after it has shifted a predetermined distance from normal position.

4. A device for the purpose set forth comprising a retainer, a carrier normally completely enclosed by said retainer and capable of being shifted for a portion of its length from one end of the retainer, impression member carrying elements pivotally connected at their inner ends to one end of said carrier, actuating means for and pivotally connected to the elements for moving them to and from stamping position with respect to the carrier, means pivotally connected to said actuating means and slidably connected to said carrier and retainer for shifting said actuating means to provide for the moving of the elements to and from stamping position, and means connected with said carrier and slidably connected to said retainer for

bodily shifting said carrier and actuating means together for a portion of their length from the retainer, whereby the carrier will be shifted from normal position, said means further providing for the return of the carrier to normal position.

5. A device for the purpose set forth comprising a retainer, a carrier normally completely enclosed by said retainer and capable of being shifted for a portion of its length from one end of the retainer, impression member carrying elements pivotally connected at their inner ends to one end of said carrier, actuating means for and pivotally connected to the elements for moving them to and from stamping position with respect to the carrier, means pivotally connected to said actuating means and slidably connected to said carrier and retainer for shifting said actuating means to provide for the moving of the elements to and from stamping position, means connected with said carrier and slidably connected to said retainer for bodily shifting said carrier and actuating means together for a portion of their length from the retainer, whereby the carrier will be shifted from normal position, said means further providing for the return of the carrier to normal position, and said retainer provided with means for limiting the shift of the carrier from normal position.

6. A device for the purpose set forth comprising a pair of impression member carrying elements shiftable to and from stamping position, a carrier having one end pivotally connected to the inner ends of said elements, pivoted means slidably connected with the carrier and to said elements for moving them to and from stamping position, a retainer for normally completely enclosing said elements, pivoted means and carrier, said pivoted means slidably connected to said retainer, and means for slidably connecting said carrier to said retainer and providing for the shifting bodily of said elements, pivoted means and carrier from normal position and projected from the retainer thereby permitting of said pivoted means to shift said elements to stamping position.

7. A device for the purpose set forth comprising a pair of impression member carrying elements shiftable to and from stamping positions, a carrier having one end pivotally connected to the inner ends of said elements, pivoted means slidably connected with the carrier and to said elements for moving them to and from stamping position, a retainer for normally completely enclosing said elements, pivoted means and carrier, said pivoted means slidably connected to said retainer, means for slidably connecting said carrier to said retainer and providing for the shifting bodily

of said elements, pivoted means and carrier from normal position and projected from the retainer thereby permitting of said pivoted means to shift said elements to stamping position, and means for limiting the shift of said carrier from normal position.

8. A device for the purpose set forth comprising a tubular retainer, a pair of oppositely movable impression member carrying elements normally completely enclosed by the retainer, and shiftable means normally, completely enclosed by the retainer, pivotally connected to said elements and provided when shifted from normal to move the elements clear of the retainer and to set the elements in stamping position.

9. A device for the purpose set forth comprising a tubular retainer, a pair of oppositely movable impression member carrying elements normally completely enclosed by the retainer, shiftable means normally, completely enclosed by the retainer, pivotally connected to said elements and provided

when shifted from normal to move the elements clear of the retainer and to set the elements in stamping position, said means further providing for the moving of the elements from set position to enter the retainer when said means is shifted to normal position.

10. A device for the purpose set forth comprising a tubular retainer, a pair of oppositely movable impression member carrying elements normally completely enclosed by the retainer, shiftable means normally, completely enclosed by the retainer, pivotally connected to said elements and provided when shifted from normal to move the elements clear of the retainer and to set the elements in stamping position, and said retainer provided with means for limiting the movement of said shiftable means when moved from and to normal position.

In testimony whereof, I affix my signature hereto.

ERWIN L. TERRY.
